UNITED STATES PATENT OFFICE.

JOHN MARTIN BRYSON AND JAMES O. DICKINSON, OF OSKALOOSA, IOWA.

ROAD-DRAG.

1,282,536.

Specification of Letters Patent. Patented Oct. 22, 1918.

Application filed December 4, 1917. Serial No. 205,468.

To all whom it may concern:

Be it known that we, JOHN MARTIN BRYSON and JAMES O. DICKINSON, citizens of the United States, and residents of Oskaloosa, in the county of Mahaska and State of Iowa, have invented a certain new and useful Road-Drag, of which the following is a specification.

The object of our invention is to provide 10 a road drag of simple, durable and inexpensive construction.

In the use of road drags, it has been found that a weighted drag when pulled along the road will smooth off very nicely 15 the surface of a dirt road where there are irregularities caused by wheeled trucks or foot prints of horses. In such cases the action of a weighted flank or blade, which is merely dragged over the road and is not mounted upon wheels is very efficient. It has also 20 been found, however, that when there is a depression of considerable size in the road, the nose of the drag will tend to dive into the depression, so that the result of the drag 25 over a depression of considerable size in the road is to deepen this depression in many cases. This result is caused by the fact that the drag will slide down into the depression as it is being pulled across and the nose of 30 the drag will tend to scrape off the soil on the ascending side of the depression as it continues its further progress. The soil thus scraped off instead of being left in the depression is carried along the succeeding 35 surface of the road and gradually deposited thereon. It has also been found that considerable difficulty is experienced in turning a road drag of the type that is not wheel mounted around when the desired 40 length of road has been dragged. In view of these well known features of the use of road drags it is the object of our invention to provide an improved road drag wherein the drag or scraper moves over the surface 45 of the road and is held against such surface by its own weight under ordinary conditions but which may be flung up onto wheels when it is expedient to remove the drag from contact with the ground.

50 A further object of our invention is to provide a comparatively long scraping blade, which may be pulled over the ground at an acute angle to the longitudinal center of the road, so that the effect upon the road 55 surface may be similar to that secured by the use of an ordinary drag while the ad-

vantage is secured inherent in the use of a cutting blade.

A further object of our invention is to provide at the rear end of such inclined 60 scraper blade an auxiliary transversely disposed blade adapted to level off and pulverize whatever dirt may be picked up and carried along to the rear end of the inclined blade.

A further object of our invention is to provide a long blade adapted to be dragged over the road surface in position inclined at an acute angle to the longitudinal axis 65 of a road and having at the rear end of 70 said blade a second transversely disposed pulverizing and leveling blade both of which may be operatively connected with an ordinary wagon or with the body of a power driven truck in such manner that the 75 side drag on the wagon or truck body caused by the inclination of the main scraper blade will be substantially neutralized.

A further object of our invention is to provide a draft rigging whereby a drag of 80 the class described may be secured to the ordinary wagon or truck body with a minimum of additional parts and in such manner that these additional parts and the drag 85 may be readily connected thereto or disconnected therefrom.

A further object of our invention is to provide a pair of arms, which may each have 90 one end pivotally and detachably secured to the wagon or truck body and which may each have their other ends pivotally mounted 95 on the main cutting blade whereby the main cutting blade may be held in position spaced from the wagon or truck body and inclined at an acute angle relative to the line of movement of said wagon or truck body. It is also our object to secure one lever to the wagon body having a chain extended between said lever and the adjacent portion of the cutting blade, so that the forward end of 100 the cutting blade may be raised or lowered relative to the ground by manipulation of said lever. The transversely disposed blade heretofore mentioned has caster wheels disposed rearwardly thereof and a second lever 105 is pivoted above said transversely disposed blade and fulcrumed above said caster wheels and also operatively connected with each end of the main cutting blade whereby manipulation of the last described lever controls the vertical position of both the transverse blade and the rear end of the main 110

blade from which it will be seen that either the forward or the rearward end of the main blade may be lifted relative to the ground whereby the surface of the road which is being worked upon may be inclined by the action of the main blade toward either side of the path of travel thereof.

With these and other objects in view our invention consists in the construction, arrangement and combination of the various parts of our device whereby the objects contemplated are attained, as hereinafter more fully set forth, pointed out in our claims and illustrated in the accompanying drawings, in which:

Figure 1 shows a top or plan view of our invention as applied to an ordinary wagon.

Fig. 2 is an elevation shown from a point in a line perpendicular to the longitudinal axis of the main scraper blade.

Fig. 3 is a vertical, sectional view taken on the line 3—3 of Fig. 1.

Fig. 4 is an enlarged vertical, sectional view taken on the line 4—4 of Fig. 1, and

Fig. 5 is an enlarged vertical, sectional view taken on the line 5—5 of Fig. 2.

Referring to the accompanying drawing we have used the reference numeral 10 to indicate generally the body of a wagon or truck, which is mounted on wheels 11. Pivotally and detachably secured to the body 10 at one side thereof just forward of a wheel 11 is an arm 12. The arm 12 may be secured to the bed 10 as is shown in Fig. 5 where an angular bracket 13 is bolted to the bed 10 at 14 and has a lateral extension 15 spaced from the bed 10 and perforated to receive a bolt 16, which also is loosely received in an opening in the end of the arm 12.

A second arm 17 is pivotally and detachably secured to the rear of the wagon or truck preferably to the rear axle thereof at a point adjacent to the side opposite that at which the arm 12 is secured. The arms 12 and 17 are designed to carry the main inclined scraper blade which is designated generally by the numeral 18. The connections of both arms to the blade 18 are similar so that only the connection of the arm 12 is herewith illustrated and shown in Fig. 4.

The blade 18 consists of one comparatively wide elongated strip to which is removably secured at the lower edge a cutting knife 19. A comparatively large angle iron extends throughout the length of the blade 18 and has a flange 20 bolted to the rear side of the blade 18 while the other flange 21 extends rearwardly and horizontally therefrom. Bolted to the rear side of the blade 18 near the forward end thereof is an upwardly extending blade 22, which has its upper edge rolled and otherwise suitably shaped to form one member of a hinge 23. The other member of the hinge 23 is a blade 24, which extends rearwardly therefrom and carries the

arm 12, the latter being pivotally secured to said blade near the forward end thereof by bolt 25.

The flange 21 is provided at either side of the blade 22 with a plurality of openings 26, which are designed to receive bolts 27 passed through one end of arms 28. The other ends of the arms 28 are secured to the rear end of the blade 24 by bolt 29. From the foregoing it will be seen that by moving the bolts 27 to the various openings 26 in the flange 21 the distance of the bolts 29 from the flange 21 may be varied, which results in varying the angle of the blade 24 relative to the blade 18. The blade 24 may be said to substantially be held from tilting movement by its connection with the arm 12.

It will be seen that the result of varying the angle of the blade 18 to the blade 24 will be to vary the angle of inclination of the blade 18 relative to the ground upon which the blade 18 may be operating. The hinge member 22 and blade 24 to which the arm 17 is pivotally secured is placed near the center of the blade 19. At the rear end of the blade 18 a transverse blade 30 is disposed, which is secured to a vertical support 31. The member 31 is the cross portion of a U-shaped or channel shaped member comprising a cross portion 31, which is vertical and the two horizontal members 32 and 33. Secured to the member 32 are a pair of rearwardly extending arms 34, which are connected at either end by a transverse angle iron 35. A plate 36 is secured to each of the arms 34 and to the angle iron 35, and carries the shank of a caster wheel 37. Between the arms 34 a plate 39 is extended between the member 35 and the member 32.

The following means are used for connecting the transverse blade with the main inclined blade and the wagon body: A chain 40 is secured to the wagon or truck preferably to the rear axle adjacent to the place where the arm 17 is secured and extends rearwardly therefrom. The chain 40 is then divided and chains 41 and 42 extend to either end of the member 31 where they are secured by means of eyes 43. A rigid hook member 44 is pivoted to the rear end of the flange 21 of the blade 18 and is adapted to be hooked through one of the eyes 43. The hook 44 is of such length that the rear end of the blade 18 will be disposed substantially at the center of the blade 30 when the rear end of the blade 18 is close to the blade 30, which is its normal position.

From the foregoing description of the parts it will be seen that we have provided means for detachably securing our inclined blade and leveling transverse blade to the rear end of the wagon or truck body in such position that forward movement of the wagon will pull the two cutting blades over the ground or road surface with little or

no tendency toward a side draft. This results largely from the fact that the connection of the arm 17 with the blade 18 is approximately at the center of the latter, so 5 that the pull of the transverse blade 30 neutralizes substantially any side pull that might result from the extension of the blade 18 to one side of the body 10.

A lever 45 is pivoted by bolt 46 to the plate 10 39 above the member 32 and extends rearwardly and forwardly from said pivot point. The rearward extension is designed to slide over the plate 39 so as to permit such loose swinging of the blade 30 as may take place 15 during the ordinary scraping movements or when the device is being turned. The portion of the lever 45 which extends forwardly is connected by a chain 47 with the rear end of the blade 18 and then extends forwardly 20 to position adjacent to the rear end of the wagon or truck bed 10.

Means such as a chain 48 and a pin 49 should be used to hold the forward end of the lever 45 in vertically adjusted positions. 25 From the foregoing it will be seen that when the lever 45 is in the position shown in Fig. 2 the blade 30 will contact with the ground and the extension 33 will be but slightly above the surface of the ground. The chain 30 47 is also of such length that the rear end of the blade 18 will rest upon the ground. When, however, the lever 45 is raised and held in raised position by means of the chain 48 and pin 49 the blade 30 and the rear end 35 of the blade 18 will be lifted from the ground and held in lifted position by means respectively of the bolt 46 and the chain 47. This results from the fact that the rear end of the lever 45 is supported by the caster wheels 37 40 and the forward end is supported by the wagon box 10, so that the intermediate portion carrying the bolt 46 and the chain 47 is raised vertically to thereby lift the above mentioned parts of the blades.

45 A second lever 50 is pivoted at 51 to the bed 10 and the chain 52 is extended from the rear end of the lever 50 to the blade 18 where it is secured in one of a plurality of 50 openings 53, which are disposed between the two blades 22. Means, not here shown, are provided for holding the lever 50 in certain 55 adjusted positions, so that when the forward end of the lever 50 is lowered from its position shown in Fig. 2 the rear end will be raised to thereby pull on the chain 52, which will raise the forward end of the blade 18 clear of the ground.

From the construction of the parts just described it will be seen that manipulation 60 of the levers 50 and 45 will respectively raise either the forward end of the rear end or the blade 18 from contact with the ground or both ends may be raised from contact with the ground when desired. The 65 blade 30 is also raised at the same time. At

the forward end of the blade 18 a plow 51 may be detachably mounted for a purpose hereinafter to be made clear. The forward edge, however, of the blade 18 when the plow is detached is curved as shown by the 70 dotted line 55.

In the practical operation of our improved road drag devices such as are shown in Fig. 5 are suitably secured to the body of a truck or wagon in order that the arms 12 75 and 17 may be detachably secured thereto and means are provided for pivoting the lever 50 to the body and means are provided for securing the chains 48 and 40 to the proper places on the body or rear axle as 80 the case may be.

When it is desired to attach our improved drag to the truck or wagon the wagon is then moved to proper position where the arms 17 and 12 may be secured thereto and 85 the chains 40, 48 and 52 secured in place.

From the foregoing it will be seen that the entire drag may be secured to a truck or wagon body in a very few minutes when it is desired to use the drag. If the road, 90 which is to be worked upon, is some distance from the place at which the drag is stored the respective levers 45 and 50 may be manipulated to raise the blade 30 and the blade 18 clear from the ground, which makes 95 it possible to transport the entire drag upon wheels to the place where it is desired to use it. When the road to be surfaced is reached, levers 45 and 50 are moved to position where the entire weight of the blades 18 and 30 100 will rest upon the ground and the operator may then drive along the road and under ordinary circumstances it has been found that no tension or adjustment is necessary in the use of the drag unless the road is in 105 very bad condition or it is desired to change the crown.

With our improved drag it is possible to adjust the parts by manipulating the levers 45 and 50 to change the crown or the slant 110 of the road from the center to the side or to make a ditch along the side of the road. It will be seen that the angle of the bottom edge of the blade to the horizontal may be adjusted to incline in either 115 direction by raising either lever 45 or the lever 50.

When it is designed to ditch the side of the road the lever 45 may be raised sufficiently to raise the rear end of the blade 18 120 off the ground and the plow 54 secured to the forward end of the blade 18, so that the inclined scraping blade having a point at its forward end is formed, so that a very clean cut ditch may be made and the earth 125 removed from the ditch will be scraped up to the center of the road.

We believe that our road drag is an improvement on others now known in that it is more efficient, that it will do the work 130

with less power and that it can be operated at a greater speed than such other devices.

The greater efficiency of our drag is obtained by the various features of its construction hereinbefore mentioned and results among other things from the use of a long blade with a sharp cutting edge, which is arranged at such an angle that it will readily and rapidly shave the road from the ditch to the center cutting off all ridges and lumps and depositing the loose dirt in low places, thus giving to the road a perfect grade from ditch to center. The transverse blade at the rear of the diagonally arranged blade may be manipulated by its controlling lever to enable the operator to shave and smooth off the center of the road and deposit all the loose dirt in wheel tracks or depressions, which may exist in the road, particularly if the road is soft and muddy. The use of this type of grader with a sharp blade makes it possible to keep weeds and grass shaved from the surface of the road from the ditch to the center thus maintaining a clean smooth surface and makes it easy to fill all the small ditches running crosswise, which might result from hard dashing rains or other causes. The drag may be used on one side of the road while leaving the other side free for traffic. The long blade may be extended to or even slightly over the ditch and yet the source of power, which draws the machine, may travel in the road on solid ground. The long blade cuts off the ridge, which tends to be formed between the ditch and the track at the center of the road thereby preventing any wash along the upper edge of such ridge and depositing the dirt in the low places in the road and producing a perfect grade from ditch to center, which allows all water to flow freely to the ditch and reduces the washing out along the road of any kind to a minimum.

Where the crown of the road may be too high or the grade from the crown to the ditch too steep, the crown may be reduced by drawing our drag along the center of the road and throwing the ridge in the center to either side. On account of the angle of inclination of the long blade with relation to the path of travel of the machine, we are able to secure more of shearing or shaving effect with less dragging of the dirt than occurs with the use of other machines thereby reducing the amount of power necessary to pull our drag. The dirt will quickly slide along the blade, so that the machine can be drawn at a greater speed than ordinary machines without interfering with the perfect smoothing and grading of the road.

Attention is also called to the ease and quickness with which the operator can make his adjustment for cutting off the high places and fill in the low spots in the road.

On account of the use of the sharp blade and the angle of the inclination of the long blade it will be seen that we can grade a harder surface road than can be dragged with the ordinary drag now in use.

Some changes may be made in the construction and arrangement of the various parts of our improved road drag without departing from the essential features and purposes of our invention and it is our intention to cover by our claims any modified forms of structure or mechanical equivalents, which may be reasonably included within their scope.

We claim as our invention:

1. In a drag, a frame mounted on wheels, a diagonally arranged blade, means for connecting said blade with said frame for dragging said blade behind the frame and for permitting the blade to be tilted for varying its angle of inclination with the surface of the ground, and for permitting it to be raised and lowered, a second frame, a substantially transversely arranged blade at the forward end of the second frame, a supporting runner device at the rear part of said second frame, a lever secured to said second frame for permitting said second frame to swing in a horizontal plane, and extending forwardly from said frame and arranged so that when the forward end of said lever is raised said second frame will be tilted for causing said runner to travel on the ground and for lifting the blade on said second frame off the ground, and a flexible member connecting said lever with one end of said first blade, whereby when said second described blade is raised off the ground one end of the first described blade will be raised.

2. In a device of the class described, the combination of a frame mounted on wheels, with a diagonally arranged blade, means for operatively hinging said blade to said frame for permitting the blade to be raised and lowered, a second frame, a blade at the forward portion thereof, a supporting runner device at the rearward portion thereof, means for tilting said second frame for raising said second blade off the ground, and a flexible means for connecting said tilting means with one end of said first blade whereby when the second blade is raised, one end of the first blade will be raised.

3. In a drag, a blade, angle iron brackets on the back thereof, hinged devices each having one end secured to said blade, arms pivoted to the other portions of said hinged devices for permitting said arms to swing laterally with relation to the hinged devices, and braces pivoted to said last named members of said hinged devices and adjustably mounted on said angle iron brackets.

4. In a device of the class described, a wheel mounted frame, an elongated cutting

blade disposed adjacent to the rear end thereof with its longitudinal axis inclined at an acute angle to the longitudinal axis of said frame, means whereby the blade may be held in position spaced from the frame and at a predetermined angle relative to the ground, a second cutting blade disposed transversely relative to the longitudinal axis of said frame at the rear end of the first described blade, a supporting frame extended rearwardly from said last described blade, supporting wheels disposed beneath the rear end of said supporting member,

means extended between said frame and said last described blade adapted to limit 15 the movement of said blade relative to said frame, a lever secured to said supporting frame rearwardly of said second blade, and flexible means for securing the second described blade and the rear end of the first described blade to said lever, and means for vertically adjusting the forward end of said 20 lever.

Des Moines, Iowa, November 16, 1917.
